UNITED STATES PATENT OFFICE

BILLIE BROOM, OF PHILADELPHIA, PENNSYLVANIA

DESIGN FOR A WEDDING RING

Application filed August 1, 1930. Serial No. 36,533. Term of patent 14 years.

To all whom it may concern:

Be it known that I, BILLIE BROOM, a citizen of the United States, residing at Philadelphia, in the county of Philadelphia and State of Pennsylvania, have invented a new, original, and ornamental Design for Wedding Rings, of which the following is a specification, reference being had to the accompanying drawing, forming part thereof.

Fig. 2 is a side view of the ring opposite one of its straight portions;

Fig. 3 is a side view from a direction 45 degrees removed from that of Fig. 2; and

Fig. 4 is a corresponding view from a direction 45 degrees removed from that of Fig. 2 and on the side opposite from the view shown in Fig. 3.

Fig. 5 is a plan view of a fragmentary portion of one of the straight sections of the ring showing the surface ornamentation more in detail.

I claim:

The ornamental design for a wedding ring, as shown.

BILLIE BROOM.
